UNITED STATES PATENT OFFICE.

BERNARD BENEDICT, OF NEW YORK, N. Y., ASSIGNOR TO BEACON MINIATURE COMPANY, INC., OF NEW YORK, N. Y., A CORPORATION OF NEW YORK.

FLASH-LIGHT.

1,250,545.

Specification of Letters Patent. Patented Dec. 18, 1917.

Application filed September 8, 1914. Serial No. 860,541.

To all whom it may concern:

Be it known that I, BERNARD BENEDICT, a citizen of the United States, and a resident of the city and county of New York and 5 State of New York, have invented certain new and useful Improvements in Flash-Lights, of which the following is a specification.

The invention pertains more particularly 10 to portable electric lamps of the character designed to be held in the hand and sometimes used as flash lights and at other times for affording a permanent light for a short period, and the object of the invention is to 15 provide a novel and efficient construction of lamp of the class referred to by which a number of objections to or defects in portable flash lights as commonly manufactured and sold, may be remedied. One purpose 20 of the invention is to avoid the accidental lighting of the lamp by the placing of the exposed metal parts thereof against a metal surface or another flash light. These flash lights are frequently carried by workmen 25 in a box of tools, and in many constructions when the flash light is placed against a metal tool the latter closes the circuit and lights the lamp, and in my construction of flash light this objection is entirely avoided. My 30 invention more particularly comprises novel means for supporting the reflector which receives the lamp, these means including a saddle secured within the upper end of the exterior shell or tubular casing of the light 35 and a threaded neck or nozzle on the reflector adapted to be screwed within a threaded opening at the center of said saddle for securing the reflector in correct and rigid 40 position and to receive the threaded socket of the lamp, the lamp and reflector being adapted to be applied to said saddle as one part and the assembling of the reflector and saddle serving to carry a terminal of the lamp against the battery terminal. The 45 saddle in its transverse member has the threaded opening to receive the threaded neck or nozzle on the reflector, said neck being both internally and externally threaded and of sheet metal. The saddle is of 50 sheet metal and in the lamp circuit and preferably is less in width than the diameter of the tubular casing so that upon the removal of the reflector from the light substantial spaces are left to receive proper implements 55 or tools whereby the battery, should the

same be stuck within the exterior casing, may be forced from the lower end of said casing. In the construction presented by me one of the more important features resides in the provision of the saddle having 60 a threaded opening in its transverse member to receive the threaded neck of the reflector carrying the lamp, this construction presenting many advantages not heretofore existing in flash lights known to me. It is 65 of manifest advantage to provide a reflector having a threaded neck to receive the lamp and to likewise provide a transverse member within the tubular casing having a threaded opening to receive the threaded neck of the 70 reflector, the reflector being thereby very readily and firmly secured and the terminal of the lamp being carried centrally downwardly in positive and firm engagement with the central terminal at the top of the 75 battery in opposition to the force of the spring usually provided within the tubular casing at the lower end of the battery.

The invention will be fully understood from the detailed description hereinafter 80 presented, reference being had to the accompanying drawings, in which:

Figure 1 is a side elevation of a portable electric light embodying my invention;

Fig. 2 is a central vertical section on an 85 enlarged scale and partly broken away of the same on the dotted line 2-2 of Fig. 1, and

Fig. 3 is a detached perspective view of the saddle which, in use, is secured within the 90 upper end of the tubular casing and receives the reflector carrying the lamp.

In the drawings, 10 designates the exterior tubular casing, usually of fiber, of the flash light, 11 the battery therein, 12 a metal cap 95 closing the lower end of said casing, 13 a metal band secured upon the lower end of said casing 10 and threaded to receive the threaded sides of said cap, 14 the customary end glass, shown as a lens, 15 the usual 100 flanged and threaded band securing said lens on the outer end of the main casing, 16 the usual threaded metal band secured upon the outer end of the casing 10 to receive the threaded sides of the band 15, 17 the reflector, 18 the lamp bulb, 19 the saddle having a threaded opening 20 in its transverse member to receive the threaded neck 21 on said reflector, 22 a customary terminal 105 extending along the inner side of the casing 10 110

and connected at its upper end with the circuit closer casing 23 and at its lower end with the metal band 13, and 24 the customary terminal extending along the outer portion of the inner surface of the casing 10 and in this instance being electrically connected with the saddle 19. The lower end of the terminal 24 is secured by a rivet 25 to the casing 10 and upon said rivet and fastened against the said terminal 24 is a spring switch 26 adapted to be engaged by a conducting member 27 carried by a thumb piece or slide 28 which is mounted on the casing 23. The parts 26, 27 constitute the main circuit closer members, and in Fig. 2 these members are shown as separated from each other, the circuit being broken. When the slide 28 is moved upwardly on the casing 23 the contact member 27 is placed in engagement with the switch 26 and then the circuit is completed due to the electrical connection of the terminals 22, 24 with each other in a manner well understood in this art.

25 The battery 11 is of the usual type and it is seated upon a spring 29, as usual.

The more important features of my invention reside in the construction provided at the outer end of the casing 10, and these features include the saddle 19 and reflector 17 having the threaded neck 21 to be screwed into the hole or opening 20 at the center of the transverse member of the saddle 19. The saddle 19 is of sheet metal having sides 30 which support the transverse member and are secured to the walls of the casing or shell 10 by means of rivets 31, the outer ends of said rivets being within the recesses formed in the shell or casing 10 so as to avoid any contact of said rivets with the band or sleeve 16. The transverse member of the saddle 19, in the construction illustrated in the drawings, spans across the interior of the shell or casing 10, as shown in Fig. 2, and said transverse member is less in width than the diameter of said shell or casing 10, whereby reasonably wide spaces are left between the side edges of said transverse member and the adjacent walls of the shell or casing 10. The reflector 17 is formed with the inwardly extending threaded nozzle 21, and this nozzle is adapted to receive the lamp end also to be screwed into the hole or opening 20 in the transverse member of the saddle 19. The upper edge of the reflector 17 is flanged outwardly, as at 32, and this outwardly extending flange 32 is seated upon the upper ends of the sides of the saddle 19 and also upon the insulating casing tube 10 and is shown in the drawings as seated upon a shoulder formed by recessing out, as at 33, the upper inner edges of the shell or casing 10. The provision of the recess 33 is to prevent electrical connection of the reflector 17 with the metal band 16, the object being

to keep the band 16 and band or cap 15 out of the electric circuit. The reflector 17 is in the circuit, because it is in engagement with the saddle 19, which is in electrical connection with the conductor 24. The conductor 70 24 extends upwardly along the outer face of one of the sides of the saddle 19, as shown at the upper right hand side of Fig. 2, and is secured against the saddle by the rivet 31, shown at said portion of Fig. 2. The threaded socket of the lamp 18 may be screwed into the threaded neck 21 of the reflector 17 and then said reflector may be screwed into the opening 20 of said saddle until the flange 32 of the reflector becomes seated within the 80 recess 33, thereafter the lens 14 may be readily applied by means of the band or cap 15. If the battery 11 is in the shell or casing 10 when the reflector and lamp are applied to position, a terminal of the lamp 85 will be carried against the usual terminal 34 of the battery in opposition to the upwardly exerted force of the spring 29. The securing of the reflector 17 in the saddle 19 is of considerable importance, since thereby 90 the reflector may not only be very firmly and evenly and centrally secured, but the spring 29 is prevented from forcing the reflector outwardly beyond its normal position, whereby the lens 14 may be very readily 95 secured upon the outer end of the casing 10.

When the switch members 26, 27 are in engagement with each other the circuit is made through the conductors 22, 24, as usual, but in this instance the circuit is 100 through the saddle 19, reflector 17 and lamp socket to the terminal 34 of the battery, the band 16 and band or cap 15 being kept out of circuit. It will be obvious that in the construction presented, the flash light could 105 be placed against a metal tool or other metal surface connecting the cap 15 and cap 12 without the lamp becoming lighted, and this in itself is an important consideration. A further important part of my invention resides in the provision of the threaded neck on the reflector to be screwed into the threaded opening in the saddle, the reflector and lamp being thereby firmly and properly held and it being rendered very 110 easy to apply the reflector and lamp and thereafter the lens. The central opening 20 in the saddle and the spaces left between the side edges of the saddle and the adjacent side walls of the shell or casing 10, 115 may be advantageously used in forcing the battery from said shell or casing should the battery by corrosion or other means become stuck therein. The thread in the opening 20 of the saddle 19 is of novel formation in 120 that the sheet metal containing said opening is at one side of the opening recessed or slit laterally and flanged upwardly at one side of said recess and downwardly at the other side of said recess, thus creating spiral 125 130

flanges which serve as a thread to receive the threaded neck of the reflector.

What I claim as my invention and desire to secure by Letters-Patent, is:

- 5 1. In a portable electric flash light comprising an exterior insulating casing part containing a battery and having an end glass, an exterior glass-holding metallic part, terminals and circuit closer, a metallic reflector, a lamp held thereby, and means for rigidly and detachably holding the reflector and lamp comprising a transverse member in the chamber of said casing part above the battery and having a central opening through which the lamp socket may project and interlocking means on said reflector and member for positively securing them together, said member being of metal and in electrical connection with one of the casing terminals and said reflector, said reflector being flanged outwardly along its outer edge and said casing part being recessed along the inner edge of its outer end to afford a seat for said flange and protect the reflector against electrical connection with the means securing the lens. 75
- 10 15 20 25 30 35 40 45 50 55 60 65 70 75 80 85 90 95 100 105 110 115 120 125 130
2. In a portable electric flash light comprising an exterior insulating casing part containing a battery and having an end glass, an exterior glass-holding metallic part, terminals and circuit closer, a metallic reflector having a threaded neck, a lamp having a threaded socket screwed within said neck, and a transverse member in the chamber of said casing part above the battery and having a threaded central opening to engage said threaded neck and positively secure the reflector and member together with the end of the lamp socket exposed through said opening, said transverse member being of conducting material and in electrical connection with one of said terminals and with the reflector, which is insulated from the adjacent exterior metal parts of the flash light by said casing part. 90
3. In a portable electric flash light comprising an exterior insulating casing part containing a battery and having an end glass, an exterior glass-holding metallic part, terminals and circuit closer, a metallic reflector, a lamp held thereby, and means for rigidly and detachably holding the reflector and lamp comprising a transverse member spanning the chamber of said casing part above the battery and having a central opening through which the lamp socket may project and interlocking means on said reflector and member for positively securing them together, said transverse member being of metal and in electrical connection with one of the casing terminals and said reflector and being less in width than the diameter of said chamber, and said reflector being insulated from the adjacent exterior metal parts of the flash light by said casing part. 110
4. In a portable electric flash light comprising an exterior insulating casing part containing a battery and having an end
- glass, an exterior glass-holding metallic part, terminals and circuit closer, a metallic reflector, a lamp held thereby, and means for rigidly and detachably holding the reflector and lamp comprising a transverse member in the chamber of said casing part above the battery and having a central opening through which the lamp socket may project and interlocking means on said reflector and member for positively securing them together, said member being of metal and in electrical connection with one of the casing terminals and said reflector, said reflector being flanged outwardly along its outer edge and said casing part being recessed along the inner edge of its outer end to afford a seat for said flange and protect the reflector against electrical connection with the means securing the lens. 80
5. In a portable electric flash light comprising an exterior insulating casing part containing a battery and having an end glass, an exterior glass-holding metallic part, terminals and circuit closer, a metallic reflector having a threaded neck, a lamp detachably held within said neck, a metal saddle having sides secured within said casing and a transverse member in the chamber of said casing above the battery and having a threaded central opening to engage said threaded neck and positively secure the reflector and member together with the end of the lamp socket exposed through said opening, said saddle having one of its sides in electrical connection with one of the battery terminals, and said reflector being insulated from the adjacent exterior metal parts of the flash light by said casing part. 100
6. In a portable electric flash light comprising an exterior insulating casing part containing a battery and having an end glass, an exterior glass-holding metallic part, terminals and circuit closer, a metallic reflector, a lamp held thereby, and means for rigidly and detachably holding the reflector and lamp comprising a transverse member in the chamber of said casing part above the battery and having a central opening through which the lamp socket may project and interlocking means on said reflector and member for positively securing them together, said transverse member being of conducting material and in electrical connection with one of said terminals and with the reflector, which is insulated from the adjacent exterior metal parts of the flash light by said casing part, the reflector having a peripheral flange adapted to seat upon said casing part. 115
7. A portable electric light having, in combination, a metallic reflector, a metallic lamp socket, a metallic plate in electrical connection with and rendering support to the reflector and lamp socket, and casing means inclosing and electrically insulating the re- 125

4
flector and lamp socket and said plate against electrical exposure at the outside of said casing means.

8. A portable electric light having, in combination, a metallic reflector, a metallic lamp socket carried by the reflector and projecting inwardly therefrom, a metallic plate provided with a socket-receiving opening for receiving and rendering support to the lamp socket and in electrical connection with the lamp socket and reflector, and casing means inclosing and insulating said reflector and lamp socket and plate against electrical exposure at the outside of said casing means.

9. A portable electric light having, in combination, a metallic reflector, a metallic lamp socket carried thereby, a metallic plate in electrical connection with the reflector and lamp socket, a metallic outer casing part, means for supporting the reflector and lamp socket and plate in electrically insulated relation to said casing part, and means including a manually operable circuit controller for including said plate in a lighting circuit.

10. A portable electric light having, in combination, a metallic reflector, a metallic lamp socket carried by the reflector and projecting inwardly therefrom, a metallic plate provided with a socket-receiving opening for receiving the lamp socket and in electrical connection with the lamp socket and reflector, a metallic outer casing part, means for supporting said reflector and lamp socket and plate in electrically insulated relation to said casing part, and means including a manually operable circuit controller for including said plate in a lighting circuit.

11. A portable electric light having, in combination, a metallic reflector, a metallic lamp socket carried by the reflector and projecting inwardly therefrom, a metallic outer casing part, a metallic supporting member for said reflector and lamp socket provided with a socket-receiving opening for receiving the lamp socket and in electrical connection with the lamp socket and reflector, an insulating casing part interposed between and electrically insulating said supporting member from said outer casing part, and means including a manually operable circuit-controller for including said supporting member in a lighting circuit.

12. A portable electric light having, in combination, a metallic reflector, a metallic lamp socket carried by the reflector and projecting inwardly therefrom, a metallic outer casing part, a metallic supporting member for said reflector and lamp socket, and an insulating casing part interposed between and insulating said supporting member from said outwardly exposed metallic casing part.

13. A portable electric light having, in combination, a metallic reflector, a metallic lamp socket carried by the reflector and projecting inwardly therefrom, a metallic outer casing part, a metallic supporting member for said reflector and lamp socket, and an insulating casing part interposed between and insulating said supporting member from said outwardly exposed metallic casing part.

14. A portable electric light having, in combination, a metallic reflector, a metallic lamp socket carried by the reflector and projecting inwardly therefrom, a metallic outer casing part, a metallic supporting member for said reflector and lamp socket provided with a socket-receiving opening for receiving the lamp socket and in electrical connection with the lamp socket and reflector, an insulating casing part interposed between and electrically insulating said supporting member from said outer casing part, and means including a manually operable circuit-controller for including said supporting member in a lighting circuit.

Signed at New York city, in the county of New York and State of New York, this 5th day of September A. D. 1914.

Copies of this patent may be obtained for five cents each, by addressing the "Commissioner of Patents, Washington, D. C."

It is hereby certified that the assignee in Letters Patent No. 1,250,545, granted December 18, 1917, upon the application of Bernard Benedict, of New York, N. Y., for an improvement in "Flash-Lights," was erroneously described and specified as "Beacon Miniature Company, Inc.," whereas said assignee should have been described and specified as *Beacon Miniature Electric Company, Inc.*, said corporation being owner *by mesne assignments* of the entire interest in said invention, as shown by the records of assignments in this office; and that the said Letters Patent should be read with this correction therein that the same may conform to the record of the case in the Patent Office.

Signed and sealed this 12th day of February, A. D., 1918.

[SEAL.]

J. T. NEWTON,
Commissioner of Patents.
